CLAIM

The ornamental design for a recessed ring handle, as shown and described.

DESCRIPTION

FIG. 1 is a perspective view of a recessed ring handle showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion circled and labeled 9 in FIG. 2; and,

FIG. 10 is an enlarged view of the portion circled and labeled 10 in FIG. 2.

The broken lines depict portions of the recessed ring handle that form no part of the claimed design. The broken lines encircling portions of the claimed design that are illustrated in the enlargements form no part of the claimed design.

1 Claim, 10 Drawing Sheets
